HANDLING AND COLLAPSING PAPER BOXES

Kenneth W. Macdonald, Watertown, Mass., as-
signor to Oskar W. Wikstrom, Newton, Mass.

Application September 3, 1937, Serial No. 162,339

18 Claims. (Cl. 93—53)

My present invention relates to mechanism for manipulating paper boxes, especially boxes of the so-called set-up type, which initially have a set-up form in the box-making machine. More particularly, it aims to provide improved methods and means for collapsing such boxes, and especially for infolding them, that is, to fold their walls in the direction toward the interior of the box. The invention includes as important objectives methods and means universally applicable for collapsing boxes of widely varying construction, sizes and proportions, and contemplates means which is constituted as a unitary organization adapted readily to be installed to receive and collapse the set-up boxes coming from box-forming or setting-up machines of various designs, including particularly machines of the type well-known under the trade-mark "Brightwood".

20 In the drawings illustrating by way of example one embodiment of the invention,

Fig. 1 is a side elevation of a box-collapsing machine or unit as a whole;

Fig. 2 is a plan of the machine of Fig. 1;

25 Fig. 3 is a longitudinal vertical section through the same;

Fig. 4 is a vertical section as on the line 4—4 of Fig. 1;

30 Fig. 5 is an elevation, on a larger scale of one of the box-engaging or carried elements of the box-receiving, transferring and aligning means, looking inwardly toward its vertical supporting axis;

Fig. 5a is a horizontal section on the line 5a—5a of Fig. 5;

35 Fig. 6 is an end elevation of the front or discharging end of the machine, that is, as viewed from the right in Figs. 1 to 3;

Fig. 7 is a section on the line 7—7 of Fig. 1;

40 Fig. 8 is an enlarged plan view of a portion of the operating means for one of the folders;

Fig. 9 is a section on the line 9—9 of Fig. 8;

Fig. 10 is a section on the line 10—10 of Fig. 8;

45 Fig. 11 is a sectional view corresponding to Fig. 9 but illustrating the folder plate in inward or down position;

Fig. 12 is an enlarged vertical sectional view 50 as on the line 12—12 of Fig. 2, showing a portion of the operating means for one folder element;

Fig. 13 is a vertical section upon the same scale as Fig. 12, taken upon the line 13—13 of said Fig. 12, looking from left to right in said figure;

55 Fig. 14 is an enlarged detail section through

one of the folder plates, as upon the line 14—14 of Fig. 2;

Fig. 15 is an enlarged plan of a portion of a pusher or ejecting device for the collapsed boxes;

Fig. 16 is a vertical section on the line 16—16 of Fig. 15;

Fig. 17 is a vertical section on the line 17—17 of Fig. 16;

Fig. 18 is an enlarged vertical section centrally through the main supporting and operating means for the receiving transferring and alignment head or turret, as on the line 18—18 of Fig. 2;

Fig. 19 is a section on the line 19—19 of Fig. 18;

Figs. 20 and 21 are respectively a side elevation and a plan, somewhat diagrammatic, of one form of means for receiving the set-up boxes, in this instance directly from the forming unit of a "Brightwood" or other box-making machine and for feeding them to the collapsing unit;

Figs. 22 to 29 are partially diagrammatic views illustrating several of the differently constructed and differently folding boxes adapted to be collapsed into flat, herein infolded, condition in accordance with the invention, wherein

Figs. 22 and 23 show the receiving or set-up and the knocked-down conditions of one form of box;

Figs. 24 and 25 are similar views of a box of a tray-like, coverless form, with rather low walls, such as represented in the preceding machine views, such for example as a so-called 3 x 4 flap-covered egg box;

Figs. 26 and 27 show the two positions of another form of box, having a flap cover and being of considerable depth, such as commonly known as a cake box; and

Figs. 28, 29 and 30 show a narrow elongated form of box, such as a cigarette carton, in its set-up position as coming from the "Brightwood" or box-making machine, its position as when fed into the collapses unit, and its collapsed position, respectively.

In general, the collapsing machine as illustrated comprises means for taking the set-up boxes coming from the box-making machine and feeding them to the receiving and aligning means of the collapses unit. Said feeding means is shown separately in Figs. 20 and 21, its inner end being seen also in Figs. 1 and 3. From the feeding means, which may be variously constructed, the box passes to a receiving, transferring and aligning mechanism, which acts also to reverse the boxes, front to back, turning them through 180° in the horizontal plane. This

mechanism, sometimes hereinafter referred to as the turret, is shown in Figs. 1 to 3 and in further detail in Figs. 4, 5, 5a, 18 and 19. It accurately presents and positions the set-up boxes to receive the action of the collapsing mechanism proper. The latter, briefly, comprises a series of folder blades or plates arranged to conform to the particular box. In the example illustrated there are four blades, each independently operated and controlled, and disposed at the four sides of a rectangle. The blades each fold inwardly in any desired sequence and timing appropriate to a particular form of box. One blade acts upon the leading vertical wall of the box, another upon the trailing wall, while the other two are disposed for infolding the side or end walls.

Boxes which have a flap cover are delivered to and acted on by the collapsing mechanism proper with their cover-carrying wall, which is usually the rear wall, foremost. Hence to avoid confusion I herein refer to the leading and trailing walls of the boxes rather than to the front and rear walls. The collapsing mechanism proper including the folder blades here referred to is seen in Figs. 1 to 3 and in further detail in Figs. 7 to 14.

Following the collapsing operation the infolded boxes are ejected from the folding station, are passed through further pressing or creasing means and are delivered to a conveyor or other suitable receiving means for collecting or stacking and packaging them. Such ejecting, pressing and delivering means is shown in Figs. 1 to 3 and in further detail in Figs. 6 and 15 to 17.

To consider first the feeding means, and referring particularly to Figs. 20 and 21 as well as Figs. 1 and 3, the boxes B are disposed in set up position upon a feed table 1, onto which they may be dropped directly from the forming box or throat 2 of a box-making machine such as the well-known "Brightwood" machine previously referred to. At the upper left portion of Fig. 20 a blank from which the box is formed is represented at b, and the vertically moving forming block or plunger means at 3. In the generality of box-making machines, such as those of the type referred to, boxes having flap covers are formed with the cover-carrying wall rearmost, so that the boxes are received on the feed table 1 with their flap covers at the rear, as seen in Figs. 20 and 21.

The boxes are advanced along the feed table 1 by any suitable means. I have herein shown for the purpose a chain 4 passing about front and rear sprockets 5 and 6. The upper run of the chain moves below a central longitudinal slot 7 in the table, and above a longitudinally adjustable bar or track 8. At intervals selected for spacing the boxes to the desired extent, the chain carries a series of dogs or pusher fingers 9 of L-shape pivoted at the outer ends of their bases. When otherwise unsupported the dogs accordingly drop to an inactive position as at the right in Fig. 20. As each dog comes up about the rear sprocket 6 it rides onto the track 8 which erects it to operative position to engage behind and advance a box, as represented at the left in Fig. 20. On delivering their boxes to the transferring and aligning mechanism at the forward or right end 70 of the table, the dogs or feed fingers ride off from track bar 8 and drop again into out-of-the-way position. By adjusting one back bar 8 lengthwise on its supports 8a the drop-off point for the dogs may be adjusted as required for different boxes.

75 It will readily be understood that the operation

of folding, and particularly infolding, the several vertical walls of a set-up box, there generally being four such walls when the box is handled in upright position, requires accurate placement and aligning of the box for proper cooperation with the folding mechanism, in order to avoid improper folding and spoiling of the boxes. For reasons which will also be apparent, and as previously noted, flap-covered boxes, which are received on the feed table with the flap carrying walls rearmost, are to be presented to the folding mechanism with the flap carrying wall in the lead. The mechanism of the invention as herein illustrated accordingly includes means not only for so accurately presenting and aligning the boxes, but also for reversing them for presentation to the folding means, and serving also to reject imperfectly formed boxes.

The mechanism as herein illustrated for the purpose is indicated as a whole by the letter T and comprises a plural-armed head or turret rotatable on a vertical axis, so that its oppositely extending arms or carrier elements C, Fig. 2, swing in a horizontal plane. This turret is operated intermittently, turning at each step through 180°, one carrier, of which there are two in the present example, being loaded from the feed table as another deposits a previously received box in position for the folding operation. In the two-carrier form shown, each acts alternately, in successive cycles, as a receiver and as a positioner for the boxes to be folded. The construction and operating mechanism for this box-receiving and positioning mechanism or turret T and its relation to the machine as a whole will now be described.

Referring accordingly to Figs. 1, 2 and 3, the machine comprises a pair of spaced side frames 15 connected by tie rods 16, two of which are seen at the lower portion of Figs. 1 and 3, and by cross bars 17, 17 at the frame ends. The side frames support the main platform or bed 20 upon which the positioning, folding and ejecting operations are carried out.

At the lower rear portion of the frames there is journaled the main drive shaft 21 for the collapsing machine or attachment as a whole; see Figs. 1 and 3. This shaft may receive power from any suitable source but preferably is driven from and in timed relation with the "Brightwood" or other box-forming machine, as by means of the chain 22 seen in Fig. 1, engaging a sprocket 24 operating a chain 25 meshing with a relatively large, reducing sprocket 26 on a cam and gear shaft 27 also journaled in the side frames. Said shaft 27 has fixed on it a gear 27a meshing with the pinion 5a on a shaft 5b rotatably supported in bearing brackets on the side frames and carrying the front sprocket 5 of the feed chain 4 already described.

Said shaft 27 also serves to drive intermittently an adjacent cross shaft 28 also supported in bearings on the side frames. For this purpose I have shown, see Fig. 3, a Geneva gear or star wheel 29 fixed on said shaft 28 and having four equally spaced radial slots 30, for successive cooperation with studs 31, 31 at diametrically opposed positions on a drive plate 32 fast on the cam shaft 27. At each half-turn of the cam shaft 27 and plate 32 one of the studs 31 engages in a slot 30 of the Geneva gear, producing a quarter-turn of the latter and its shaft 28, and a quarter-turn dwell.

Viewing now also Figs. 4, 5, 6, 18 and 19, the shaft 28 has fixed on it near its central portion

a bevel gear 35 meshing with a bevel pinion 36 fixed at the lower end of a short upright shaft 37 for swinging the turret. Said turret shaft 37 is rotatable in a bushing 38 in a bearing plate 39 secured as by bolts 39^a at the under face of the bed 20. The shaft has a supporting collar 40 above which it is received in a hub 41 at the under face of the main central portion, plate or casting 42 of the rotary turret device, said plate comprising two oppositely disposed T-like sections, as viewed in plan, as best seen in Fig. 2.

The bevel gears 35, 36 previously mentioned have a ratio of one to two, so that a quarter-turn of the shaft 38, through the medium of the described Geneva gearing, will rotate the turret shaft 37 to swing the turret through 180°. The turret plate 42 in turn supports the two box-carriers C which accordingly are stepped around or indexed about a vertical axis to present them alternately in box-receiving and box-presenting positions.

Said carrier elements C, while oppositely arranged, are similarly constructed, so that a description of one of them will suffice. Each of the opposed T-shaped sections of the turret plate 42 has at its outer face a series of slotted ears 43, of which there are four in the illustrated example, those of each series being alined to provide a guideway for slidably supporting the box-engaging arms 44, 44 of the corresponding carrier unit C. Each such arm 44 has a foot 45 at its inner end adjustably secured as by the bolt 46, see particularly Figs. 5 and 5a, to a slotted slide 47 received in said guideway provided by the ears 43. By varying the positions of the arms 44 relative to their slides 47, as permitted by reason of the slots 47^a in the slides and the connecting bolts 46, the carriers may readily be adjusted for cooperation with boxes of widely differing dimension transversely of the machine, as for example from about 5 inches or less up to about 17 inches or even more in some cases.

The arms 44 of each carrier C are moved toward and from each other at the proper times, to position, grip, or to release, a particular box B. In the illustrated example the arms are drawn inwardly toward each other as by a spring 48, Fig. 5, extending between posts 49 on the respective arm slides 47, whereby the arms have capacity for yielding in their inward box-engaging movement.

For the purposes to be more fully described, the arms have three different positions, an outermost or full open position, a partly closed position, and a full closed position in which they grip the box. These positions are determined by separating elements or spreaders 50, Figs. 4, 5 and 5a in the form of two-armed rockers, one rocker at each end of a short horizontal rock shaft 51 journaled in the turret plate 42, for cooperation with the respective carriers C.

The inner ends of the arm slides 47 are recessed as at 47^b, allowing them to approach substantially into engagement with the shaft 51, and providing abutment members 47^c at the inner ends of the slides, for engagement by the ends of the corresponding rocker 50, to move the slides and the arms 44 oppositely away from each other when the shaft 51 is rocked.

Noting particularly Figs. 18 and 19, the shaft 51 has pinned on its central portion, above the vertical axis 37 of the turret as a whole, a double-armed rocker 52 each of the diametrically opposed arms 53 of which have a foot 54 located for alternate engagement by a push pin or tappet 55

supported for vertical movement in the machine bed 20. The tappet is urged downwardly as by a coil spring 56 seating between a collar 56^a at its lower end and the under face of a portion of the bed, downward movement of the tappet being limited by a collar 55^b.

This spreader tappet 55 is operated through appropriate connections with the cam shaft 27 previously referred to. As seen in Figs. 1 and 3, said shaft 27 carries a cam 60 having duplicate opposite half portions each including raised sector 61, a sector 63 of intermediate height and a low portion or sector 64. Cooperating with the cam is a roll 65 on a cam lever 66 pivoted at one end on a bracket 67 (Fig. 4) on the rear cross-bar 17. The inner end of the cam lever 66 has a foot 66^a underlying the tappet 55; see also Fig. 18. The cam 60 accordingly controls the tappet 55 and the rocker 52, to open the arms of the two carriers C or to permit them to close as desired. It will be noted that the arms of both carriers are moved simultaneously and to the same extents, whichever arm of the rocker 52 is over the tappet 55 at the particular time.

The functions and operation of the box-receiving and positioning means or turret will readily be understood from a consideration of Figs. 1 to 3, and particularly Fig. 2. In the latter the arms 44 of the two carriers C are shown in full lines in their full open position and in dotted lines in their intermediate and full-closed positions.

Assume now that the full-line positions shown in Fig. 2 are those in which the carrier C then at the left receives a box B and the then right-hand carrier deposits the preceding box at the folding station, to be more fully described later. At this time a high portion 61 of the cam 60, which turns in the clockwise direction as viewed in Figs. 1 and 3, is under the cam roll 65. Thereafter the cam-roll drops to a cam portion 63 of intermediate height. The carrier arms accordingly close to their intermediate dotted-line positions, in which they move inwardly through a major portion of their total movement, for example, seven-eighths thereof, so that they closely approach but do not grip the boxes. This partial closing action of the righthand carrier serves to align and recenter the box just previously deposited by it at the folding station, in case it has been displaced in dropping from the carrier, and accurately presents the box to the folding means to be described. The similar and simultaneous partial closing of the lefthand or rear carrier has the effect of causing the incoming box to enter between the arms with some friction. The inward movement of the box is limited by an adjustable stop, one for each carrier, shown as a strip 42^a adjustably fixed on the turret plate 42.

As the next step a low portion 64 of the cam comes opposite the roll 65, allowing the tappet 55 to drop to its lowermost position, so that the arms of both carriers close in fully toward each other, under the action of their springs. The folding of the box now takes place while turret dwells one-half cycle. The carrier C still at the left in Fig. 2 accordingly grips the box B previously received between its arms. Thereupon the turret indexes around through 180°, under actuation of the described Geneva gearing, transferring the box from the receiving position at the end of the feed chain to a position over the folding station, at the right in Fig. 2. The carrier previously referred to as being at the right hand side of the turret at the same time swings around rearwardly into position to receive the next incom-

ing box. The described cycle of operation is then repeated, it being noted that each cycle occurs during a half-rotation of the duplicate-halved cam 60 in the example shown, to conform to the 5 two roll Geneva cam which makes one-half revolution to one cycle of the machine.

From the foregoing it will be seen that the set 10 up boxes are received and fed into the collapsing machine in upright position and with their open side up, the boxes traveling along a horizontal plane. The collapsing action is also performed with the boxes in said upright position and with their open side up, with the exception of certain special instances in which the boxes may be fed 15 and folded with one side wall uppermost, or in other position, to meet the requirements for some particular folding arrangement for certain boxes.

The folding or collapsing is done at the folding 20 station F, Fig. 2, provided by the upper flat surface of the bed 20. The bed and the folding station thereon preferably are in substantially the same horizontal plane in which the boxes are received and forwarded, so that the entire action, including the initial reception, feeding, transferring 25 and aligning, and collapsing, as well as the further folding and delivery of the collapsed boxes to the collection, stacking or delivery point, takes place not only in a horizontal plane but also in substantially the same plane throughout 30 the entire machine. This makes for simplicity, speed and accuracy in the handling of the boxes and reduces likelihood of jamming or other irregularities.

Referring again to Fig. 2, the collapsing or 35 folding mechanism proper comprises, a series of blades, plates or folding elements, herein generally referred to as folders, and usually corresponding in number to the number of vertical walls of the particular box, although in some cases 40 a folder may not be required at some one or more walls. In the illustrated form, designed primarily for collapsing rectangular boxes, there are four such folders, one externally adjacent each vertical wall of a box deposited in upright position at the folding station F. While in some instances 45 two or more of the folders may operate in unison and in the same manner, the invention contemplates provision whereby each folder is independently operable, each being controllable by its own actuating mechanism, herein illustrated as of a cam and lever construction. Hence, depending 50 on the form and setting of the several cams, the individual folders may be timed to function in any required sequence, and to have any desired 55 dwell in folding position. For example, any two or more of the folders may operate simultaneously, or each may be moved to fold or to return at different times. Further, any of the folders may have a repeating, double or other plural operation, 60 with one or another of the other folders acting intermediately.

As best seen as a whole in Fig. 2, the folding mechanism accordingly includes a front folder 70 variably controllable by a cam 71. At the near 65 side of the folding station as viewed in Fig. 1, or at the lower central portion of Fig. 2, is one of the side folders 90 actuated from a cam 91 at the same side of the machine. Another folder 110, for the trailing wall of the box, extends 70 transversely at the rear of the folding station F and is controlled from its cam 111 seen at the upper left portion of Fig. 2. A fourth folder 130, for the other box side, is disposed oppositely to the side folder 90 and is controlled from its cam 75 131, at the upper right in Fig. 2.

It will be noted that the operating mechanism for one transverse folder and one longitudinally extending folder, for example the front folder 70 and side folder 90 and including their cams 71, 91 are disposed at one side of the machine, while 5 that for the other two folders is at the other machine side. This mechanism at the two sides may be substantially the same, and hence a detailed description of that at one side will be sufficient.

10

Referring now to Figs. 1, 3 and 4, the cam 91 for the right side folder 90 is fixed on a cam shaft 92 journaled in suitable bearings in the side frames, the cam 111 for the rear folder 110 being mounted on the same shaft, at the other side of 15 the machine. This shaft is driven by a gear 93, Fig. 3, meshing with the similar gear 93a on the main drive shaft 21. The several cams here referred to are illustrated as of the face type, having closed cam paths at their inner faces, 20 those for the cams 91 and 71 being indicated at 91a and 71a respectively in Figs. 1 and 4.

As seen in said Figs. 1 and 4, the path 91a of the right side-folder cam 91 receives a cam roll 94 on a cam lever 95 rocking on a stud 96 on the 25 adjacent side frame. The free end of the cam lever 95 is connected through an adjustable pivoted link 97 with a transverse arm 98, see also Figs. 6 and 7, extending from a collar 99 fixed on a short longitudinal shaft 100 supported for 30 rocking movement in a bracket 101 on the adjacent right side frame 15. Provision is made not only for lengthwise adjustment of the link 97, as by means of the turn buckle construction illustrated, but also for adjusting its point of pivotal 35 attachment to the arm 98, as by means of a boss 98a on the latter having a plurality of openings 98b for selective reception of the pivot pin 98c for the upper end of said link; see particularly Fig. 7.

Fixed on said short shaft 100 is a second collar 102 carrying a vertical arm 103 pivoted at its upper end to a short horizontal link 104, the other end of which is pivotally connected with an ear 105a depending from a slide 105.

40

As seen on a larger scale in Figs. 8 to 11 inclusive, the slide 105 is demountably connected as by a screw 105b, Fig. 9, to the under face of a rack 106 having opposite side flanges 106a, Fig. 10, supporting it for sliding movement, transversely 50 of the machine, on track members 106b on the side walls of a slot 106c in the bed 20; see also Fig. 2.

45

Referring still to Figs. 8 to 11, the rack 106, thus supported for movement transversely of the 55 machine, toward and from the folding station F, meshes with a toothed segment 107a on a rocking plate-carrier 107. The side folder plate 90 previously referred to is demountably secured to said carrier 107 as by means of the screws 107b. The plate carrier 107 is supported for rocking movement between its normal or inactive position of Fig. 9 and its infolding position of Fig. 11 by means of a pin 107c in the forked portions 108a of a fixed but adjustable block 108, by shifting 65 which the location of the folder 90 may be varied for cooperation with boxes of different sizes or types. To afford such adjustment a clamping plate 109 underlying the block 108 and received in a grooved way 109a cut in the bed 20, at the opposite vertical walls of the rack slot 107c. The block 108 and plate 109 are adapted to be clamped together and to the bed 20, at various appropriate selected positions along the path of a rack 70 106, as by a clamping screw 108b.

75

The opposite side folder 130, at the left of the machine, is seen in plan at the upper portion in Fig. 2 and in elevation in Fig. 3. As previously noted, its supporting and operating means may 5 be the same or substantially the same as that already described in connection with the right side-folder 90, with particular reference to Figs. 8 to 11. Portions of the left side-folder mechanism, for operating the folder plate or blade 130, are 10 seen in Figs. 2, 3, 6 and 7, where they are designated by the same reference numerals but with the addition of a prime mark as used for the corresponding portions of the mechanism for the right folder 90 above described. In this connection it is noted that in the illustrated example the arrangement of the two cams 131 and 111 at the left side is the reverse of that at the right. That is, the cam 131 for the left side-folder 130, corresponding to the cam 91 for the right side-folder 20 90, is not on the same shaft 92 with said cam 91 but is fixed at the left end portion of a second or front cam shaft 72, see Figs. 1 and 6, which carries the cam 71 for the front folder 70, about to be described in more detail. In other words, 25 at the right side of the machine the cam 71 for the transverse (front) folder 70 is in front of the side-folder cam 91, while at the other side the relative arrangement of the two cams is the reverse, the cam 111 for the transverse (rear) folder 30 being behind the cam 131 for the left side-folder 130, as is readily apparent from an inspection of Fig. 2.

Turning now to the construction and operating means for the transversely extending folder plates 35 or folders 70 and 110, their description will be directed chiefly to that for the front folder 70, since the construction and operating connections for the latter and the rear folder 110 may be and are herein illustrated as substantially identical, 40 similarly as in connection with the two side-folder mechanisms. As in the case of the latter, similar reference numerals are applied to corresponding parts of the front and the rear folder mechanisms, with the addition of prime marks for those 45 of the rear folder.

Considering now Figs. 1 and 6, the front folder cam 71 is adjustably fixed on the forward cam shaft 72 above mentioned, the latter being suitably journaled in bearings on the opposite side frames. This forward cam shaft 72 is driven 50 through a sprocket 72^a fixed on it and receiving a chain 73 passing around a similar sprocket 92^a, Figs. 1 and 4, on the rear cam shaft 92 which in turn is driven by the gears 93, 93^a, Figs. 3 and 4, from the drive shaft 21, as previously described.

The cam path 71^a of the front folder cam 71 receives a cam roll 74, Fig. 1, on a cam lever 75 rockably supported on the adjacent side frame as at 76. The free end of the cam lever is pivotally connected through a longitudinally adjustable link 77 to the lower arm 78 of a bell crank mounted for rocking movement on a stud 79 on the adjacent side frame. Provision desirably is made for variably connecting the link 77 and arm 78, in a similar manner as previously described in connection with the side-folder connections, as by means of the plural apertured boss 78^a, Fig. 1, for receiving the upper pivot of the link 77, at different selected locations.

The upper arm 80 of the bell crank, Figs. 1, 6, 7, and particularly Figs. 12 and 13, is pivoted to one end of a link 81 pivoted at its other end to a lug 82^a depending from a slide 82. The latter is demountably connected as by screws 82^b, 82^c, Fig. 13, at the lower face of a toothed rack 83

having side portions 83^a slidably received on a track formed by opposed shoulders 83^b on the side walls of a longitudinally extending slot 83^c in the bed 20; see also Figs. 2 and 4.

The sliding rack 83, actuated through the cam 5 71 and the described connections serves to rotate a pinion 84 having an integral split sleeve 84^a received on the reduced outer end portion of a short cross shaft 85. A collar 84^b and set screw 84^c adjustably secure the pinion on said shaft. 10

The shaft 85 is rotatably supported in a bushing 85^a in a bearing block 86, and has an end piece 85^b extending inwardly beyond the latter, as best seen in Fig. 12. Connected flatwise to said shaft extension 85^b is a bar 87 extending 15 transversely of the machine, herein for substantially the full width thereof, as seen in Fig. 2. The other end of said bar 87 is similarly supported by a short transverse shaft 85^a in a bearing block 86^a. 20

The cross bar 87 provides the direct support for the front collapses plate or folder 70. The latter is demountably connected to the bar as by means of a series of screws 70^a received in apertures tapped in the bar. As best seen in Fig. 4, 25 in connection with the rear folder 110 and its similar supporting cross bar 87', a multiplicity of such apertures is provided substantially along the entire length of these bars, adapting them for the interchangeable reception of folder plates 30 of widely differing length, as appropriate for boxes of various different extents in the direction across the machine.

The entire front folder unit and likewise the rear folder unit, the corresponding parts of 35 which latter are designated by the same reference numerals with the addition of prime marks, are arranged for bodily adjustment, in the direction lengthwise of the machine, to position them as required for boxes of different extent in the direction lengthwise of the machine. The construction in this connection is the same at each end of each of the folder-carrying bars 87 and 87', that for the right end of the front folder bar 87 being seen in detail in Fig. 12. The 40 bed 20 is formed with longitudinal grooves 88, 88', one at each side portion; see also Fig. 2. Said grooves are undercut, Fig. 12, for the slideable reception of clamping plates 89, one for each of the several bearing blocks 86, 86^a, etc. 45 The latter have downwardly projecting ribs 86^a guided in the upper portions of the corresponding groove 88 or 88'. Clamping screws 89^a extending downwardly through the blocks and into their clamping plates serve to clamp or release 50 them with respect to the bed 20. Thus the pair of blocks 86, 86^a at the ends of the bar 87 for the front folder, and similarly the blocks 86', 86^a' which carry the bar 87' for the rear folder, may readily be adjustably shifted lengthwise the bed 55 20 so as to present the front and rear folders in proper operative position for collapsing the given box.

From the preceding description it will be seen 60 that the several folder devices and their operating mechanisms are adapted for independent operation, so that the time of their actuation, the extent of their rocking or folding motions, and the speed and duration of these motions are each 65 separately and positively controllable and may 70 readily be varied, for any one or more of the folders, to meet the requirements for the particular box and type of fold. The folder motions depend on the timing, speed and extent of motion of the respective racks 83, 83' and 106, 106' 75

which in turn are controlled by the timing and conformation of the corresponding cams 71, 81 and 111, 131. It will be noted, particularly with references to Figs. 1, 2 and 7, that said cams are herein located outside the machine frames and where they are readily accessible for adjustment or interchanging with cams of different shapes.

The several folders have been referred to individually with respect to their location on the machine, the delivery end of the latter, at the right in Figs. 1 to 3, being considered as the front of the machine. The folder 70, nearest the front of the machine, accordingly is termed the front folder, and the folder 110 opposed to it is termed the rear folder, irrespective of the particular wall of a box upon which they operate. As previously noted, in the great majority of cases the boxes are delivered to the folders in upright position, with open side up, and boxes which include hinged cover flaps, usually at the upper edge of their rear walls, are presented with their flap-carrying or rear wall at the front of the machine, adjacent the front folder, so that the flap may be folded over toward the rear of the machine, allowing the collapsed box to be ejected from the folding mechanism with the free edge of its flap in trailing position. Thus while the front folder will always operate on that wall of the box which is presented in leading position, and the rear folder acts upon the trailing wall, such leading and trailing walls may be the rear and the front walls respectively, or other walls, of the boxes themselves. In other words, the terms front and rear as applied to the folders have reference to their location on the machine, and not to the particular portion of the box upon which they may operate in any given case.

The motion of the folders, for example the front folder 70, is readily seen from a comparison of Figs. 9 and 11. In Fig. 9 the folder blade or plate 80 is shown in its normal or inactive upright position. Its path of folding movement in rocking about its point of pivotal support 107 is indicated by the curved arrow. In Fig. 11 the same folder 70 appears in its inmost or substantially its inmost folded position, wherein it is substantially horizontal. The described provisions for adjustments allow any less extent of inward angular folding movement intermediate the positions of Figs. 9 and 11 to be had, as by shifting the link 97 relative to the arm 80, pivoting it at any selected aperture of the series.

It will also be noted that the folder blades themselves have their lower edges at a level above the upper face of the machine bed 28, and that the folders are always vertically spaced from the latter, so that the collapsed boxes may readily be moved out from the folding station even though one or more of the folders may be turned down in position such as that of Fig. 11. This spacing of the folders above the bed allows an ejecting or forwarding device, to be described, to enter below the folders so as to engage and advance the collapsed box to the further folding or pressing and delivering means.

In Figs. 22 and 23 I have illustrated somewhat diagrammatically the folding operation for a box of a tray-like flap-covered type such as also represented in the various views of the machine, the latter being assumed to be set up for collapsing this particular box, merely by way of example. One common box of this type is the so-called "3x4" one-dozen egg box. The type of fold illustrated in said Figs. 22 and 23 is that known in the trade as the "B-fold", wherein the side walls

are infolded first, along creases extending diagonally from their bottom corner portions, as indicated by the lines a, a in said figures. These creases define on each side wall a substantially triangular portion having its base along the lower edge of the wall. Said section is turned down into substantially flat position against the inner face of the bottom of the box, in the collapsed position, and the remaining triangular upper corner or ear-like portions of the side wall are turned over reversely and flatwise onto the outer face of the infolded triangular portions, in the further course of the collapsing action including the infolding of the leading and trailing walls of the box. The resulting collapsed or partly collapsed position of the box is represented in Fig. 23, for comparison with its initial or set-up position as in Fig. 22.

Referring still to said Figs. 22 and 23, the side folders 90 and 130 in this instance are selected to have a shape and dimension conforming generally to that of the triangular section of the side walls, as clearly seen in Fig. 22. Since in this example the body of the box is relatively shallow, so that the side walls when infolded do not meet or overlap each other, the side folders 90 and 130 may be set to operate simultaneously. Accordingly, as the first step in this particular folding operation illustrated in Figs. 22 and 23, the side folders 90 and 130 are first rocked inwardly toward each other, folding the triangular sections of the side walls inwardly and at the same time tending to draw the leading, flap-carrying wall and the trailing wall inwardly toward each other. The side folders in this case have a short quick in and out action, their cams being shaped to afford the desired rapid short single throw. As the side folders move out, the rear folder 110 is turned inwardly, as controlled by its individual cam. The inward movement of the rear folder 110 is of sufficient extent and duration to turn in the trailing wall of the box and hold it in position to be engaged and held down by the inward overlapping onto it of the leading wall and its flap cover. The rear folder may in this instance be withdrawn to its upright position prior to descent of the flap cover or may be allowed to remain down until the box is ejected.

The front folder 70 in this case may operate simultaneously or substantially simultaneously with the rear folder, or slightly after the latter, as determined by its individual cam control. In this case it has but a single action or throw, but has a dwell, in inturned position, of sufficient duration to retain the entire box in its collapsed state, by engagement over the outer face of the leading wall, until the box has been ejected from the folding station and engaged between the presser rolls to be described. As or immediately after the collapsed box leaves the folding station all of the folders again stand in upright position, in readiness to receive the next incoming set up box.

In the example just described in connection with Figs. 22 and 23 it will be seen that each of the several folders has but a single action, that is, is rocked inwardly but once. Also, the side folders operated in unison as a pair, and the front and rear folders also act in unison but somewhat after the side folders. Further, the side folders in this instance had what I herein term a short throw, that is, they were withdrawn quickly after their inward movement. The motion of the rear folder was of either the short throw or the long throw type, the latter referring to a motion in

which there is some dwell in the infolded position. The front folder had a long throw, but a single action, being left in for a somewhat longer period, for the purpose above noted. The type of box and fold shown in said Figs. 22 and 23 represents one of the less complex folding problems, in which two or more of the folders may be permitted to act in unison due mainly to the fact that the particular box shown is relatively shallow, so that its side walls do not require to be overlapped relatively to each other.

In Figs. 24 and 25 I have illustrated the set-up and the collapsed or partially collapsed positions of another form of box, also of a relatively shallow tray-like form, such as a pie or pastry container, without cover means. Or the device shown in said figures may be considered as typical of a flanged cover element, it being understood that my machine is equally adapted to the collapsing of such covers, the term "box" being used herein throughout as inclusive both of the body or container elements and also the reversely positioned cover or top elements.

The box of Figs. 24 and 25, being relatively shallow, and having no flap cover, has no two opposing walls which overlap in the collapsed condition of the box. The fold again is of the "B" type, as in Figs. 22 and 23, the infolding triangular or truncated pyramidal portions of the side walls again being defined by diagonal fold creases *a*, *a*. The direction of travel of the boxes, in the first manner of folding the boxes now to be described, is indicated by the full-line arrows. The action of the side folders, which again are shaped and dimensioned to conform substantially to the infolded area of the side walls between their fold lines *a*, *a*, may be the same as in Figs. 22, 23. The front and rear folders, for operating on the non-creased opposite walls seen at the upper right and lower left in Figs. 24, 25 may in this instance also operate as a pair, in unison, each having a single throw. Said front and rear cams however each have a relatively long throw, retaining their inturned positions for a sufficient period to insure the delivery of the box to the subsequent mechanism in its collapsed position. It will be noted, both with respect to the box of Figs. 22, 23 and that of Figs. 24, 25 that the leading wall is folded inwardly and rearwardly, away from the direction of travel of the box, so that the latter will readily be received in the nip of the succeeding presser rolls.

Here again, referring to Figs. 24 and 25, each of the folders requires but a single action, having but one in and out movement, and the folders may operate in pairs, those of each pair in unison, but with one pair, that above referred to as the side folders, acting in advance of the other. But due to the capacity of the machine for universal and individual adjustment of the several folders, a box of the coverless type as in Figs. 24, 25 may be fed through the machine in a position turned 90° from that previously described, so that its advancing movement would be in the manner indicated by the dotted-line arrows in Figs. 24 and 25. In that case the front and rear folders would be timed to operate first, in unison and each with a single short throw, followed by the operation of the side folders, which in this case would engage the uncreased walls, acting in unison and each with a single but long throw, to retain the box in collapsed position.

In Figs. 26 and 27 I have shown the set up and collapsed or partially collapsed positions of an-

other type of box, again having a flap cover. In this case the box is so proportioned that both pairs of opposed walls must partially overlap, in the respective pair, in the folded position. The folding problem in this instance accordingly is relatively complex, but may be handled with equal facility by the collapsing mechanism of my invention, largely by reason of the capacity for individual control of the several folders.

In the box of said Figs. 26 and 27 the trailing wall includes a central triangular section *t* defined by fold lines *t'*, *t''* extending diagonally from the bottom corners. The rear folder blade is here shaped and proportioned to conform to said section *t*. The latter is turned in as the first step in the folding operation, the rear folder being arranged to have a single short throw. The side walls are in this case provided with fold lines *s'*, *s''* extending diagonally from the front bottom corner and defining a main section *s* substantially as indicated in the figures. The side folder blades here employed are of a size and shape to conform to said side sections *s*.

Immediately following, or during the last portion, of the return motion of the rear folder, one or the other of the side folders are operated, first the one for the side wall which is to underlie a portion of the other one. If the side folders were actuated in unison in this instance the two side walls, each of which is of an extent exceeding one-half the dimension of the box from side wall to side wall, the upper edges of the side walls would come into contact and cause a jam. Hence one side folder is timed to operate in advance of the other, as permitted by their individual control mechanism. The motion of the side folders is a single action but is of the long throw type, the folders remaining in their inward or down position at least until the leading wall of the box is infolded and, if preferred, until the completely collapsed box is engaged by the ejecting mechanism. This dwell for the side folders is desirable in view of the additional number of folded thicknesses of material and the correspondingly increased tendency of the parts to spring upward if prematurely released.

As the final operation, in folding the box of Figs. 26 and 27, the front folder is rocked inwardly, with a single long throw, acting to turn the leading wall rearwardly and downwardly and to hold the entire box in its collapsed position for ejecting and delivery to the presser rolls. It will be noted that in this case each of the four folders is actuated at a different time and that but one of them, the rear folder, has a short throw, the other three having long throws. Each folder, however, has but a single action, that is, one motion in and out. The type of fold as illustrated in connection with Figs. 26 and 27 is that sometimes referred to in the trade as the "A-fold", in which three of the vertical walls have portions which are folded over onto themselves.

Turning now to Figs. 28 to 30, I have there illustrated a container of the cigarette carton type, presenting a different folding problem. The box, as in the previous instances, is delivered from the Brightwood or other box-making machine in the upright position and with the flap-carrying wall at the rear, as in Fig. 28, similarly as in Figs. 20 and 21 illustrating the feeding mechanism. In this instance, however, the box is tripped or otherwise turned during its reception at the feeding station, as by means of a finger *f*, indicated in dotted lines in Fig. 20, which engages beneath the rear edge of the box and

causes it to turn forwardly through 90° so as to assume a position on the feed table as illustrated in Fig. 29 wherein the flap cover extends forwardly from one of the longitudinal walls, then 5 uppermost and in horizontal position. In the course of the transfer of the box by the turret, from the feed table to the folding station F, the box is reversed in the horizontal plane, bringing the projecting flap to the rear, as in Fig. 30.

10 In the following folding operation the bottom wall of the box, then in the leading position, and the two end walls are in effect doubled inwardly along their then horizontal median creases, indicated by the reference characters *m* 15 and *m'* in Figs. 28 to 30. The bottom wall also has diagonal fold lines *m''* extending in from the adjacent corners and meeting the median line *m*. The front folder blade is shaped and dimensioned to conform to the lower half portion of the leading (bottom) wall of the box, defined between 20 the median line *m*, the two opposite end diagonals *m''* and the bottom edge of the wall.

To collapse the box, the front folder is first actuated with a short quick throw, to start the 25 formation of an inturned V-shaped trough at the leading (bottom) wall. Following the quick withdrawal of the front folder the two side folders are turned in, also with quick short throws, producing inturned V-formations at the ends of 30 the box, as seen in Fig. 30. The rear folder in this case is dispensed with. Following a quick withdrawal of the side folders, the front folder receives a second inward motion, this time with a long throw, so that it is turned down upon the 35 outer face of the then upper flap-carrying longitudinal wall of the carton. The front folder at this time has a dwell of sufficient duration to retain the box in collapsed position for its ejection and advance to the presser rolls.

40 It will be noted that in this instance, Figs. 28 to 30, one of the folders, the front folder in this particular case, receives a double actuation, first of the short-throw type and secondly a long throw. Similarly, a double action may be afforded 45 for the side folders to assist in holding down the multiple thicknesses of material at the ends of the box.

Such double action may be provided wherever necessary or desirable, for any one or all of the 50 four individual folders. The two actuations may in any case consist of two short throws, two long throws, or one short and one long throw, in either order. Moreover, in connection with some collapsing operations one or another or all of the 55 folders may receive a plural actuation in the course of which they are moved in and out more than twice. These various motions, permissibly differing for each folder, are made possible through the individual cam control and connections for the respective folders and the capacity 60 for ready adjustment or interchange of the controlling elements for cams, rendering the mechanism universal in its application to the collapsing of boxes of various types and sizes.

65 The means for initiating the forward movement of the collapsed boxes, out from the folding station, and its operating mechanism appears in Figs. 1 to 3, and 6 and in more detail in Figs. 15 to 17. Said means, referred to as the ejecting 70 mechanism, herein comprises a pusher element or block 140 normally standing behind the rear folder 110 and mounted for longitudinal reciprocating movement along the machine bed 20. A forwardly projecting interchangeable plate 141 75 is demountably attached at the upper face of the

pusher block 140, as by screws 141*, Fig. 17, said block and plate together forming the pusher element proper, for direct engagement with the box. The projecting plate 141 is adapted to engage over the infolded trailing wall of the collapsed 5 box, or other rear portion thereof, and the front face of the block 140 is arranged to abut a trailing edge portion, so as to push the flattened box forward to the presser rolls, to be described.

The pusher block 140 is adjustably connected 10 through an underlying laterally flanged block 142 and screws 143 with a slide 144 having lateral flanges 144* guided on shoulders 145 at the sides of a guide slot 146 in the machine bed 20. It will be seen that by removing the plate 141 and 15 loosening the adjusting screws 143 the pusher block 140 and its underlying carrier block 142 may be released from the slide 144, so that they may be shifted lengthwise the latter, correspondingly to adjust the position of the pusher element 20 relative to the folding station F, to adapt it for cooperation with boxes of different size.

The ejector or pusher element is operated 25 through suitable connections with a cam provided for the purpose. The slide 144 is demountably connected as by screws 148 to a head 147, as best seen in Figs. 16 and 17. The latter has pivoted to it as at 148 a slotted connecting link 149 pivoted at its other end as at 150 to the upper end of a rock arm 151; see also Figs. 1, 3 30 and 6. Said rock arm is mounted at its lower end on an intermediate cross shaft 152 journaled in the side frames. This shaft 152 is rocked at the appropriate times by means of a short arm 153 fixed on the shaft and pivoted at its upper end as 35 at 154 to the adjacent end of a reciprocating cam lever 155. Said lever is forked at its opposite end as at 156 to receive sliding support on the cam shaft 72 previously referred to as carrying the folder cams 71 and 73. At an intermediate point 40 the lever 155 carries a roll 157 received in a path 158 formed in a side face of the ejector cam 159, the latter being fast on said cam shaft 72.

Through the operation of the pusher or ejector 45 cam 159 and the described connections the pusher element 140, 141 is advanced at the proper time, moving along the slot or track 146 in the bed 20, to engage a collapsed box and forward it for further folding or creasing, where such treatment is desired, and for delivery.

50 Referring again to Figs. 1, 2, 3 and 6, I have provided at the front end of the bed 20 a plurality of pairs of opposed spring-pressed rollers, herein including a rear pair 160, 161 and a front pair 162, 163. The several rollers are rotatably supported in brackets 164 on the upper front portions of the respective side frames 15. The lower rollers 160 and 162 as herein shown have their axes fixed, while the upper rollers 161, 163 are journaled in blocks 165 vertically movable 55 in ways formed in the brackets 164. Said upper rollers are yieldably urged toward the lower ones as by springs 166 bearing between the blocks 165 and cap bars 167 removably secured at the upper portions of the brackets 164. The tension 60 of the springs may be adjusted to vary the pressure applied by the rollers, to suit the particular requirements for a given box, as by means of the adjusting screws 168.

The two pressure rollers of each pair desirably 70 are positively driven, the upper ones being provided with gears 164*, 163* respectively meshing with similar gears 160*, 162* on the shafts of the lower rollers. The latter are herein driven through a chain 170, Figs. 1 and 6, passing about 75

sprockets on the shafts of each lower roll and down around a large sprocket 171 fast on the cam shaft 72 recently referred to.

The collapsed boxes as advanced from the folding station by the described ejector mechanism are moved in between the rear pair of rolls. Overlying guide means may be provided between the collapsing station and said rolls, such as the two-part guide plate 169, Fig. 3, (not shown elsewhere) the two parts of which are relatively adjustable lengthwise the machine as by means of bolt and slot connections 169^a, to conform to different settings of the front folder. The folded boxes are advanced by the rear rolls under pressure to and through the forward pair of rolls 162, 163, intermediate upper and lower guides 169^b, 169^c desirably being provided on the roll brackets 164, between the rear and front pairs of rolls, and also in front of the latter in some cases. From the rolls the flat boxes pass to any suitable delivering or stacking and handling means, such as the endless conveyor belt 175 supported on the machine frame or independently, as may be more convenient, and represented more or less diagrammatically in Figs. 1 and 3. It will be understood that the successive boxes after being presented in set-up condition to the folding mechanism are infolded by the latter so as to assume substantially their collapsed position, and that any further creasing or compressing action necessary to retain the boxes in their flattened or collapsed state is supplied, to the desired and adjustable degree, by the final pressure and delivery rolls 160 to 163. The collapsed boxes may be taken from the delivery conveyor 175 or the similar means provided, in stacks or lines of the desired number, in readiness for bundling and shipment.

It will be apparent from the foregoing that my invention contemplates method and means for taking set-up boxes from a box-making machine, of which a "Brightwood" is a typical example, advancing and collapsing them in an infolding manner, and delivering them in readiness for shipment or use. The machine or unit as illustrated may readily be coupled to such box-making mechanism, substantially as an attachment therefor, thus making the collapsing feature available for any such mechanism without material alteration and in such fashion that the collapse unit may easily be unhooked and temporarily set aside if it is not desired to collapse the set-up boxes; or it may in the meantime be coupled to another box-making machine. Heretofore, so far as I am aware, in any instance in which a box is made in set-up form and then collapsed as a part of the manufacturing process, any collapsing mechanism has been an inseparable element of the box-making machine, so that if such machine were to be used the collapsing mechanism necessarily also had to be employed and boxes could not be delivered without knocking them down, thus limiting the utility of the given machine.

As also above pointed out my method and machine which latter may be termed a universal infolder, provide for handling numerous types and forms of box infolds, handling constructions in which one or more of the walls are of greater height or dimension than one-half the extent of the box in their infolding direction so that an overlapping action is necessary in collapsing them, as well as other arrangements. Moreover, by performing the collapsing and forwarding action along substantially a single and horizontal

path, in continuation of the path along which the set-up boxes are taken from the "Brightwood" the entire operation is simplified and speeded up, with maintained or increased accuracy in the collapsing operation.

My invention is not limited to the exemplary embodiment herein illustrated or described, and I set forth its scope in my following claims.

I claim:

1. Mechanism for collapsing set-up paper boxes, comprising, in combination, a frame, supporting means thereon for the reception of the set-up boxes, a plurality of folder elements each movable about a fixed horizontal axis to turn inwardly a vertically disposed wall portion of a box received on said supporting means, and independently controllable actuating means for each folder element.

2. An organized mechanism for collapsing set-up paper boxes, comprising, in combination with a frame, a turret device adapted to turn about a vertical axis to engage and present successive boxes in collapsing position at a collapsing station, said device including a plurality of radially extending elements each having opposed horizontally movable members engageable with the individual boxes, means for moving said members toward and from each other at timed intervals so as to grip and release a given box and then to re-approach sufficiently to align said box at the collapsing station, and means for turning the turret device.

3. An organized mechanism for collapsing set-up paper boxes, comprising, in combination with a frame, a turret device adapted to turn about a vertical axis to engage successive boxes at a receiving position and to present them for collapsing at a collapsing station, said device including a plurality of radially extending elements each having opposed movable members for approaching, gripping and releasing a box, means for so moving said members at timed intervals, means for turning the turret device, and controlling operating mechanism for said means so arranged that between each turning of the turret device one of said elements then at the receiving position first opens, then partly closes to receive, then withdraws from, and then grips an incoming box, and at corresponding times another of said elements then at the collapsing station deposits a preceding box, then re-approaches and aligns it, and then withdraws to permit the collapsing action.

4. In an organized mechanism for handling set-up paper boxes, a rotary box-receiving and presenting unit having a plurality of box-handling elements, said elements including opposed jaw-like members relatively movable to open and to close to controlled extents, means to turn said unit step by step, and means affording to said jaw-like members a plurality of opening and closing movements for each step of said unit.

5. In an organized mechanism for handling set-up paper boxes, a rotary box-receiving and presenting unit having a plurality of box-handling elements, said elements including opposed jaw-like members relatively movable to open and to close to controlled extents, and drive connections for said unit and elements comprising a cam shaft, a gear shaft, intermittent gearing between said shafts effecting a quarter turn of the gear shaft for each half turn of the cam shaft, one-to-two gearing connections between the gear shaft and the unit, and a cam element on said cam shaft affording to said jaw-like

- members a plurality of opening and closing movements for each half-turn of the cam shaft.
6. In paper-box handling mechanism, a rotary device forwarding set-up boxes including a rotary 5 supporting element, a plurality of pairs of jaw-like members disposed radially of the axis of said supporting element, means for opening and closing said members horizontally at predetermined times to grip, to release and to re-approach so as to position a set-up box, and means for intermittently turning said rotary element to present the jaw-like members successively in box-receiving and box-depositing positions.
7. Mechanism for collapsing set-up paper 10 boxes, comprising, in combination, means providing a station at which the set-up boxes are presented in collapsing position, an inwardly movable folding element externally adjacent each upright wall of a box so presented, and means 15 for moving said elements each to engage and infold its corresponding box wall, simultaneously as to any two or more of said elements or each individually and in such order as required by the folding characteristics of the given box.
- 20 8. Mechanism for collapsing set-up paper boxes, comprising, in combination, means providing a station at which the set-up boxes are to be presented in collapsing position, a plurality of normally erect blades, each paralleling an upright wall of a presented box, there being at least one blade for each such upright box wall, means mounting each blade for inward swinging movement about a stationary horizontal axis at its lower portion, and a control cam and operating connections for each blade individually.
9. In mechanism for collapsing set-up paper 25 boxes, a substantially horizontal support for a set-up box, a plurality of infolding blades mounted on stationary horizontal axes along the boundary of the support, at least one blade adjacent each of the upright box walls, means to rock the blades inwardly to collapse a box received between them, and means whereby the timing and order of movement of each blade may be varied 30 with respect to any other blade.
10. In paper box manufacture, apparatus for receiving rectangular set-up boxes from box-forming mechanism and transferring and collapsing them, said apparatus comprising a frame 35 adapted to be positioned at the delivery end of the forming mechanism, rotary transfer and positioning mechanism mounted on said frame to turn on a vertical axis, conveyor means to receive the set-up boxes from the forming mechanism and to advance them to said transfer and 40 positioning mechanism, operating means for the conveyor means and the transfer and positioning mechanism to drive them in timed relation with the forming mechanism, means on said frame presenting a collapsing station, inwardly movable normally upright folding plates having stationary horizontal axes, one plate for each vertical wall of the box, the several plates in their upright position defining sides of a rectangle at 45 said collapsing station, said transfer mechanism including gripper devices to engage a box on the conveyor means, to carry the box during movement of the transfer and positioning mechanism and to deposit the box in horizontally reversed 50 position downwardly between the upright folding plates, means driven in timed relation with the forming mechanism, the conveyor means and the transfer and positioning mechanism to swing the folding plates inwardly to engage and fold in the 55 respective vertical walls of the box to collapse 60 the latter, means to move out the collapsed boxes from the collapsing station, and means further to flatten and deliver the collapsed boxes.
11. In paper box manufacture, in combination, conveyor means to receive and advance rectangular set-up paper boxes from a box-forming mechanism, said boxes constructed and arranged to be collapsed by infolding, a folding station including box-supporting means and a horizontally pivoted normally erect folder blade for each of the then vertical walls of a box, transfer and positioning mechanism successively to engage and deposit each set-up box downwardly between and in alignment with the erect folder blades at the folding station, means to turn 15 each blade inwardly on its pivot toward the positioned box so as to engage and collapse inwardly the corresponding box side wall, a main drive element, and individual operating connections between the latter and the turning means for 20 each folder blade to actuate each of them in any desired order and timing relatively to each of the others as may be required for a given box structure.
12. In mechanism for collapsing set-up paper 25 boxes, a substantially horizontal support for a set-up box, a plurality of infolding blades mounted on stationary horizontal axes along the boundary of the support, at least one blade adjacent each of the upright box walls, means to 30 rock the blades inwardly to collapse a box received between them, at least one of said blades having its axis spaced vertically above said horizontal support by at least the thickness of a collapsed box, and means to eject the collapsed 35 boxes horizontally from said support and beneath said vertically spaced blade.
13. Mechanism for collapsing set-up paper 40 boxes, comprising, in combination, supporting means providing a station at which the set-up boxes are presented in collapsing position, an inwardly movable folding element externally adjacent each upright wall of a box so presented, means for moving said elements each to engage and enfold its corresponding box wall, simultaneously as to any two or more of said elements or each individually and in such order as required by the folding characteristics of the given box, a 45 pair of cooperating presser rolls beyond the collapsing station and adapted to receive and advance the collapsed boxes between them, and means to forward the collapsed boxes from said station to the rolls.
14. Transferring and collapsing mechanism for 50 set-up paper boxes, comprising, in combination, a frame, box-supporting means thereon providing a collapsing station, a turret mounted on the frame for rotation about a vertical axis, gearing means for rotating the turret intermittently, said 55 turret including radially disposed carrier elements having a transverse guide formation at their outer portions, slide members in said guide formations, a radially projecting arm laterally adjustably secured to each slide member, said arms for each carrier element being disposed in 60 opposed pairs for movement with said slide members toward and from each other, spring means urging the arms of each pair toward each other, a rocker member disposed between the adjacent inner ends of the slides of each carrier element, 65 a rock shaft on the turret having said rocker members fixed thereon, and means for intermittently rocking said shaft to separate or to permit the closing together of the arms of the corresponding carrier element.

15. Transferring and collapsing mechanism for set-up paper boxes, comprising, in combination, a frame, box-supporting means thereon providing a collapsing station, a turret mounted on the frame 5 for rotation about a vertical axis, gearing means for rotating the turret intermittently, said turret including radially disposed carrier elements having a transverse guide formation at their outer portions, slide members in said guide formations, 10 a radially projecting arm laterally adjustably secured to each slide member, said arms for each carrier element being disposed in opposed pairs for movement with said slide members toward and from each other, spring means urging the 15 arms of each pair toward each other, a rocker member disposed between the adjacent inner ends of the slides of each carrier element, a rock shaft on the turret having said rocker members fixed thereon, and means for intermittently rocking 20 said shaft to separate or to permit the closing together of the arms of the corresponding carrier elements, said last means including a lateral projection on the rock shaft, an actuating element engageable therewith in the different positions to 25 which the turret is rotated, and means to control the operation of said actuating element.
16. Collapsing mechanism for set-up paper boxes comprising, in combination, a frame, means thereon for presenting a box in collapsing position, a transversely extending folder and opposed side folders operatively disposed at said station, said folders supported for inturning about stationary horizontal axes, means to receive a set-up box with a given wall foremost and to deposit it in 30 horizontally reversed position within the area defined by said folders, an individual control cam for each folder, means to drive the cams, and 35
- operating connections between each cam and the corresponding folder whereby each folder may be afforded an inturning movement either as a short throw or as a long throw and of selected duration, and predeterminedly as a single or as a plural 5 in-and-out action at the desired times.
17. Mechanism for receiving and collapsing set-up, paper boxes, comprising, in combination, a frame, box-supporting means thereon providing a collapsing station, means to advance set-up boxes 10 toward said station with a given wall foremost, transfer means to receive and present the boxes at the collapsing in horizontally reversed position, a plurality of normally erect folder blades mounted at said station for inturning pivotal movement 15 about stationary horizontal axes, each blade disposed externally adjacent a different vertical wall of the boxes deposited at said station, and, for each folder blade, a control cam, a slide guided on the bed for reciprocating movement at right 20 angles to the axis of its folder blade, operating connections between the cam and slide including a cam lever and adjustable linkage, a rack fixed to the slide, a blade carrying element providing the pivotal support for the blade, and a toothed 25 member on said carrying element and meshing with the rack.
18. Mechanism according to claim 17 including front, rear and opposite side folder blades, the cams for the front and one side folder blades 30 being disposed externally of the frame at one side thereof, and the cams for the rear and the other side folder blade being arranged externally at the other side of the frame, cross shafts journaled on the frame and having said cams demountably 35 fixed thereon, and drive means for said shafts.

KENNETH W. MACDONALD.
